LIQUID DISPENSING PUMP

Albrecht Larsen, Kenosha, Wis.

Application January 7, 1931. Serial No. 507,078

17 Claims. (Cl. 221—100)

This invention relates to a liquid dispensing apparatus. Generally it relates to a liquid dispensing pump of the type used for dispensing fuel.

It has for one object to provide a device in which the overflow tank is located within the housing of the pump and close to the dispensing tank. Another object is to provide an overflow tank of a size sufficient to accommodate the entire contents of the dispensing tank. A further object is to provide a dispensing tank of such design that it may be connected with a main tank underground by a single pipe and in which adequate overflow provision is made without the necessity of using more than one pipe or connection from the pump to the storage tank underground.

Other objects will appear from time to time in the specification and claims.

My invention is illustrated more or less diagrammatically in the accompanying drawings, wherein—

Figure 1 is an elevation of the pump installed, with parts in section;

Figure 2 is a vertical cross section taken at right angles to the plane of Figure 1;

Figure 3 is a vertical cross sectional detail showing the outlet valve of the overflow tank;

Figure 4 is a sectional detail showing the means for receiving and locking the hose nozzle;

Figure 5 is a detailed sectional view, showing the hose engaging member;

Figure 6 is a plan view of a portion of the nozzle on an enlarged scale;

Figure 7 is a detailed view showing in elevation a closing member for the hose nozzle opening.

Like parts are designated by like characters throughout the specification and drawings.

A indicates a foundation which may be of any suitable material to support the pump. Generally it will be of concrete or stone and will be supported on the ground. A¹ is a housing for the lower part of the pump assembly and houses the actual pumping unit. The housing A¹ may be of any suitable design and its particular details form no part of the present invention. It is sufficient that it support and enclose the pump mechanism and support the upper portion of the pump assembly. Supported on the housing portion A¹ is a partition or division A² which forms the bottom of and carries a casing or housing A³ which forms in itself an overflow tank. At its top the portion A³ is closed by a division A⁴ which forms the top of the overflow tank and the bottom of the actual dispensing tank. This latter is preferably formed by a housing or containing mem-

ber A⁵ which is normally transparent, being usually made of glass so that the contents of the tank may be seen at all times. The dispensing tank A⁵ is closed at its top by a member A⁶ which may be perforated as at A⁷ and has a transparent member A⁸ closing the perforation A⁷. A cover member A⁹ may be superimposed on top of the pump and overlies the member A⁶. It may or may not be transparent. Frequently an advertising device will be substituted for the member A⁹. Tie members A¹⁰ may be used to hold the parts in position and to engage and hold the transparent walls of the dispensing tank A⁵ in position. Similarly tie members A¹¹ may be used within the housing A¹ and they serve, among other purposes, to hold the partition member A² in position on the housing member A¹. A¹² is a storage tank normally located under the ground. It may be closely adjacent to the pump or may be widely separated from it.

B is a pipe leading from the tank A¹² and having a check valve B¹ at or near its lower end. This valve permits liquid to be drawn into the pipe B, but prevents it from running out of the pipe at its lower end. It thus serves to prevent back flow from the pump into the storage tank. Adjacent its upper end the pipe B has a second check valve B², which additionally serves to prevent liquid from running back down the pipe B. The pipe B is connected at its upper end to a pump B³ which may be of any suitable type and may be driven by a shaft B⁴ from any suitable power source. None is here shown as the details and method of driving the pump form no part of the present invention. B⁵ is a discharge pipe running from the pump B³ upward. It may run through the overflow tank A³ and into the dispensing tank A⁵, into which it discharges. B⁶ is a baffle situated at the upper or discharge end of the pipe B⁵. As shown, the pipe B⁶ is made of several sections. It might, of course, be made of one continuous section of pipe. Its purpose is to deliver liquid from the pump to the dispensing tank. B⁷ is an overflow pipe running from the dispensing tank A⁵ to the overflow tank A³. B⁸ is a pipe running from the bottom of the overflow tank to the pipe B adjacent the point of connection of the latter with the pump B³. Preferably the point of connection of the pipe B⁸ with the pipe B is above the upper check valve B².

A float operated valve is positioned within the overflow tank A³, adapted to control discharge of liquid from that tank to the pipe B⁸. This valve is preferably positioned in a removable plate C which is fastened to the partition member

A² by screws C¹ or any other suitable attaching means. C² is a bracket fixed to the plate C and having a sliding bearing portion C³ within which is slidably mounted a shaft C⁴. At its lower end is the shaft C⁴ is provided with a needle point C⁵. Adjacent its lower end a pin C⁶ is positioned. A valve member C⁷ is mounted about the lower end of the shaft C⁴. The member C⁷ is hollow as shown and the cavity within it is enlarged as at 10 C⁸. The pin C⁶ lies within the cavity C⁸. The needle point C⁵ is adapted to be seated within the cavity C⁸ to close the discharge passage C⁹ from the cavity. C¹⁰ is a lever pivoted on the bracket C² as at C¹¹ and carrying at its free end a float 15 C¹². The lever C¹⁰ is slotted as at C¹³ and a pin C¹⁴ which passes through the shaft C⁴ is positioned in the slot C¹³.

D is a dispensing outlet connection from the dispensing tank A⁵. It is preferably provided with 20 a connection portion D¹ to which a hose D² may be fastened. At its opposite or free end the hose has a nozzle D³ which is provided with a laterally extending flange D⁴ which has a forwardly extending annular flange D⁵. In this flange is 25 formed an inclined groove D⁶. A handpiece D⁷ to which the hose and the nozzle are attached, is provided with a valve, not shown in detail as its details form no part of the present invention. The function of the valve is to prevent discharge 30 of liquid from the nozzle unless the valve is positively operated to permit discharge. An operating member is indicated for the valve as at D⁸ and a handle or lever D⁹, which is pivotally mounted on the nozzle portion as at D¹⁰, may be 35 used to open the valve. D¹¹ is a keeper within which the end of the handle D⁹ is positioned. The keeper serves to limit the extreme outer movement of the handle D⁹ and otherwise prevents its displacement or injury.

40 E indicates a member or members preferably fastened to the casing A³ and upon which the nozzle may be hooked when not in use.

F is a short section of pipe positioned opposite a perforation F¹ in the casing A³. It projects inwardly into the casing and into the overflow chamber formed thereby, as indicated generally in Figure 2 and in detail in Figure 4. The inner end of the member F is cut off as shown and has mounted upon it a valve member F²⁰ which is 45 pivoted thereon and adapted to swing downward to the closed position of its own weight, as indicated in Figure 1. At its outer end the member F is provided with a flange F² which may be fastened to the housing or casing A³ by bolts F³ or 50 by any other suitable means. Fastened also to the member F in any suitable manner is a short tubular section F⁴ which is provided at its outer or free end with a laterally extending flange F⁵. Mounted on the section F⁴ and held against displacement by the flange F⁵ is a locking and tightening part F⁶. As shown it is generally annular in shape and has a cavity F⁷ within which is 55 positioned a pin or projection F⁸. F⁹ is a laterally projecting handle portion formed as a part of the member F⁶ and preferably provided with a perforation F¹⁰. This member as a whole is positioned on the tubular extension F⁴ and is free to rotate about it. The pin F⁸ may project into the groove D⁶ of the flange D⁵ of the nozzle.

70 G is a locking member of angular shape as shown in Figures 2 and 4. It is preferably pivotally mounted on the housing A³ as at G¹. It is provided with a contacting nose or point G² and a perforation G³. It may be used as indicated in 75 Figure 4 to lock the ring F⁶ and when in this posi-

tion the nose or contact portion G² will contact the lever D⁹ of the nozzle to hold it in the open position to permit discharge through the nozzle.

H is a closing member provided with a projection or enlargement H¹ within which is an inclined groove H². This groove preferably corresponds in size and shape to the groove D⁶ in the nozzle flange D⁵. Extending from one side of the member H is an extension H³ which is provided with a perforation H⁴.

I is an electrical conduit or connection from 80 which a conduit I¹ leads upwardly to an electric light I² which is situated between the member A⁶ and the cover A⁹ and preferably over the glass portion A⁸ so that the light may pass through 85 into the dispensing tank A⁵ and illuminate it and its contents.

J is a baffle plate which may be positioned 90 within the tank A⁵ and is preferably on a level with the 10 gallon marker, although this is not 95 an essential feature. It may be fastened to the bottom of the tank by screws J¹ about which are positioned tubular spacers J². Positioned on the baffle plate and preferably punched up from it are generally vertical baffle members J³.

100 It will be realized that whereas I have here-with shown and described a practical operative device, nevertheless many changes might be made in the size, shape, number and disposition of parts without departing from the spirit of my 105 invention and I wish, therefore, that my showing be taken as in a sense diagrammatic.

The use and operation of my invention are as follows:

When the pump assembly is generally in operation and fluid is being discharged more or less 110 periodically, the nozzle is not in position in the tubular section F. It is either actually in use dispensing fluid or is hung on the hook-like member E. The pump will be operated to draw fluid 115 in the storage tank A¹² through the pipe B, past the check valves B¹ and B², into the pump itself and thence upwardly through the pipe B⁵ into the dispensing tank A⁵. From this tank it is withdrawn through the hose and nozzle and 120 discharged. If for any reason the pump furnishes fluid to the dispensing tank more rapidly than it is withdrawn therefrom the fluid will overflow 125 into the pipe B⁷ and into the overflow tank formed by the member A³. It will be assumed 130 that this tank has been entirely emptied. The valve C⁷ will have been seated and the needle point C⁵ will have been seated in the valve C⁷ so as to close the opening C⁹ from it. Therefore, 135 when fluid first comes into the overflow tank it cannot be discharged. When the level of fuel within this tank rises sufficiently it will raise the float member. The first effect of this is to move the shaft C⁴ upwardly, thus unseating it and opening the passage C⁹ without at first moving 140 the valve member C⁷. This opening effect requires relatively little lifting effort but as soon as it has occurred some flow takes place through the interior of the member C⁷ out through the opening or discharge passage C⁹. As soon as this 145 has occurred the sealing effect is broken and further upward movement of the shaft C⁴ in response to further raising of the float will bring the pin C⁶ in contact with the member C⁷ and thereafter further upward movement of the 150 member C⁴ will raise the valve C⁷, unseating it and entirely opening the discharge from the overflow tank to permit free discharge through the pipe B⁸. The flow of fluid which then occurs through the pipe B⁸ is to the pump. The check

valve B² prevents, in a great measure at least, the flow of fluid down through the pipe B. If any leakage occurs past the check valve B² the discharge of fluid from the pipe B into the storage tank is further resisted by the check valve B¹.

If the pump is not in operation the fluid will stand in the pipe B⁸ or will flow into the pump and if the pump is of such construction as to make it possible, some fluid may flow upward from the pump, seeking its own level. When the pump is put in operation again fluid is first drawn from the pipe B⁸ and the valve C⁷ is again seated as soon as the level of fluid within the tank A³ has been reduced sufficiently to lower the float C¹² to close the valve.

When the apparatus is to be put out of use, for example at night, the motor is, of course, not running and the nozzle is inserted in the tubular section F. Being somewhat longer than that section it raises the valve F² into the position shown in Figure 4. The flange of the nozzle is also brought into contact with the flange F⁵. The ring F⁶ is moved so that the pin F⁸ engages the slot or groove D⁶ and draws it into locking contact. The locking member G is then moved from the position shown in Figure 2 into that shown in Figure 4 and the padlock or other locking means is inserted so as to pass through the perforation G³ and the perforation F¹⁰. The nozzle is thus locked in this position.

When the member G is moved into the position shown in Figure 4, its contacting end G² strikes the lever D⁹ and moves it so as to open the discharge valve in the nozzle. Thus the nozzle is open and extends directly into the overflow tank A³. In this fashion a direct connection is established from the dispensing tank A⁵ to the overflow tank A³. Since the discharge valve in the nozzle is held open, fluid will flow from the tank A⁵ through the hose and nozzle and into the tank A³. By proper manipulation of the hose the tank A⁵ may be entirely drained. With the parts located in the position shown in Figure 4, if an appreciable quantity was originally in the tank A⁵, the tank A³ will be filled sufficiently to raise the float C¹² and open the discharge valve from the overflow tank. Fluid will flow downward through the pipe B⁵ as above described but will not flow below the check valve B² except for such relatively slight leakage as may occur.

When the parts are to be used again if the pump is started it will first draw fluid from the overflow tank through the pipe B⁸. This will remain unobstructed by the valve C⁷ until the tank A³ has been practically emptied. Then the valve will close and further operation of the pump will draw fluid from the storage tank. Thus by holding the fluid in the overflow tank and by having this tank in the pump housing itself, the pumping line from the storage tank to the pump is kept constantly full and the necessity of priming is avoided. When the pump is used again the nozzle, of course, is withdrawn from the position shown in Figure 4. If it is desirable, the member H may be inserted in the passage F¹ to close the opening through the tubular member F. If this is done, the ring F⁶ is manipulated so that the pin F⁸ lies within the groove H² and the movement of the ring draws the parts H¹, H² into closing position, closing the opening through the tubular member F. The member G may be moved into the position shown in Figure 4 when this is the case, and a locking member, such as a padlock, may

be inserted through the perforation G³ and the perforation H⁴.

The dispensing tank may have any sort of indicator mounted in it to show its contents. Such an indicator is suggested at K.

The baffle plate J and its associated parts tend to prevent disturbance of the liquid within the dispensing tank so that when outward flow is shut off, and particularly when it is shut off suddenly, the liquid in the tank is not disturbed and, therefore, it is not necessary to wait until the disturbance which might have been caused subsides before making an accurate reading of the contents of the tank to determine the amount discharged.

I claim:

1. A liquid dispensing assembly, including a dispensing tank, a pipe system to the dispensing tank, a pump in said pipe system adapted to move fluid to the dispensing tank, a check valve below the pump, an overflow tank having an opening to receive a nozzle and adapted to receive overflow from the dispensing tank, a draining connection from said overflow tank to said pipe system, a discharge valve positioned to control draining from the overflow tank, a hose adapted to discharge fluid from said dispensing tank and adapted to be moved to discharge fluid into said overflow tank, a valve for controlling discharge through said hose and means for locking said hose in open position.

2. A liquid dispensing assembly, including a dispensing tank, a pipe system to the dispensing tank, a pump in said pipe system adapted to move fluid to the dispensing tank, a check valve below the pump, an overflow tank having an opening to receive a nozzle and adapted to receive overflow from the dispensing tank, a draining connection from said overflow tank to said pipe system, a discharge valve, positioned to control draining from the overflow tank, a hose adapted to discharge fluid from said dispensing tank and adapted to be moved to discharge fluid into said overflow tank, said overflow tank being of a capacity as great as that of the dispensing tank.

3. A liquid dispensing assembly, including a dispensing tank, a pipe system to the dispensing tank, a pump in said pipe system adapted to move fluid to the dispensing tank, a check valve below the pump, an overflow tank having an opening to receive a nozzle and adapted to receive overflow from the dispensing tank, a draining connection from said overflow tank to said pipe system, a discharge valve, positioned to control draining from the overflow tank, a hose adapted to discharge fluid from said dispensing tank and adapted to be moved to discharge fluid into said overflow tank, and means for locking said hose in open position in communication with said overflow tank, said overflow tank being of a capacity as great as that of the dispensing tank.

4. A liquid dispensing assembly, including a dispensing tank, a pipe system to the dispensing tank, a pump in said pipe system adapted to move fluid to the dispensing tank, a check valve below the pump, an overflow tank having an opening to receive a nozzle and adapted to receive overflow from the dispensing tank, a draining connection from said overflow tank to said pipe system, between the pump and the check valve, whereby fluid from the overflow tank is returned to the pump, a discharge valve, positioned to control draining from the overflow tank.
